UNITED STATES PATENT OFFICE.

LOUIS WOJIDKOW, OF BROOKLYN, NEW YORK, ASSIGNOR TO NEW YORK STAMPING COMPANY, OF BROOKLYN, NEW YORK, A CORPORATION OF NEW YORK.

DESIGN FOR A CARRIER FOR CASSEROLES AND LIKE CONTAINERS.

52,124.

Specification for Design.

Patented June 18, 1918.

Application filed April 24, 1918. Serial No. 230,595. Term of patent 14 years.

To all whom it may concern:

Be it known that I, LOUIS WOJIDKOW, a citizen of the United States, residing at Brooklyn, in the county of Kings and State of New York, have invented a new, original, and ornamental Design for Carriers for Casseroles and like Containers, of which the following is a specification, reference being had to the accompanying drawing, forming part thereof.

The figure is a perspective view of a carrier for casseroles and like containers, showing my new design.

I claim:—

The ornamental design for a carrier for casseroles and like containers, as shown.

LOUIS WOJIDKOW.
